John Bushell Dayton Ohio

Letter Patent

The subscriber referred to in this Letter Patent and in the part of the same reciting a description in the words of the said John Bushell himself of his invention in the machine for making Shingles

Be it known that John Bushell of Dayton Tippacanoe County State of Indiana has made an improvement in the use of arts, being a machine for turning the blocks of timber and raising, pointing, and shaping the Shingles out of a block of Shingle timber, which is described as follows, as per the best mode of making the several Shingles, making parts of this specification

This machine consists of the following principal parts, the frame or carriage and supporting the different parts of the machine, the frame is a roller upon which the timber is placed to be cut into blocks, blocks the same with which it is cut the apparatus with which it is used is applied into Shingles, the pointing plane with the nail under side, the hand carriage upon which the Shingles are placed, planes and carriage for shaping or turning the Shingles, the hand carriage, the planes and tools on the water wheel shafts for giving motion to the different parts of the machine

The frame is of a structure of timber timber and is adapted to its size given to strength necessary to support the several parts of the machine as applied to making Shingles. The part of the frame which is open to receive the timber to be placed upon rollers is located at one end of the machine

Log carriage. Made in a frame & by given a sufficient weight resting on a bell is attached to the pointing apparatus and works upon all of the frame upon which the timber is laid and held down by dogs and sent at into the several tools for Shingles by the motion of the carriage

Cutting or third carriage. for raising or splitting the blocks of timber into Shingles a part of the frame carriage and a part of a structure on the carriage upon which the bell is placed to be raised

Cutting pointing plane. made of iron on the side of the plane are

1184

upwards much higher than which the shingles to be joined are placed. The plane carriage having the hands to move and both hands against which the shingle is held is made to an opening in the frame and under the plane carriage upon which the side piece of the carriage is made which the shingle rests in an inclined plane which covers the shingles to be cut, thrown at the first and then at the hind end forming the point and bulk of the shingles by the plane cutting off more at the point than at the butt.

Two plane irons, M. A. one before the other are placed in the plane carriage. The front plane iron by itself and the hinder plane iron by a belt & driver. This plane carriage is attached to a handspike worked by a crutch, which causes it to move forward & back and upon may be placed in the frame.

When the plane carriage is attached to the under side of it is a lever working in a pin in a post or Standard to turn for raising the plane carriage when required to support the hand carriage with the shingles.

The whole machinery is arranged to work each part separately or all together as suits the operator.

Cap a timber. The machinery being put in position by the worker which is made ready to work by the power of steam horses, otherwise, the timber to be cut into blocks or bolts is placed upon the rollers on the frame at the end of the machine and secured by the dogs so as to cut a proper length. The block is then brought down upon the bed which is cut out with blocks or bolts for shingles. These bolts are next removed & the splitting a rising hump, to three pieces interlocking by the action of the shingle to the plane carriage as before. The shingles are then joined by being placed on the bed and held in position with the joining plane on the side of the carriage frame one side at a time and changed. The shingles are then placed on the hand frame and secured by the hands and the hand frame with the shingle stick under the plane frame and the shingle by the plane, the point of interlocking forced by the action of the plane frame to form the inclined plane formed on the hand frame. When the planing ceases the plane frame is raised by the lever & taken off and under the frame come the shingle stick upon the plane frame let down, over the other side of the shingle stick, the a bolt being now may be used as a shingle fast.

The invention here claimed and desired to be secured by Letters Patent consists of the peculiar arrangement & combination of the several parts of the improved machine for making strings.
